Inventor;
William J. Burge

United States Patent Office.

WILLIAM J. BURGE, OF ATCHISON, KANSAS.

Letters Patent No. 66,126, dated June 25, 1867.

IMPROVED KNIFE-CLEANER.

The Schedule referred to in these Letters Patent and making part of the same.

Be it known that I, WILLIAM J. BURGE, of Atchison, in the county of Atchison, and State of Kansas, have invented a new and useful improvement in Knife-Cleaners; and I do hereby declare that the following is a full, clear, and exact description of the construction and operation of the same, reference being had to the drawings, making part of this specification, in which—

Figure 1 is a perspective view.

Figure 2, a longitudinal elevation.

Figure 3, a transverse elevation.

My invention consists of a handle, A, figs. 1, 2, and 3, of peculiar form, made of wood or other material resembling a jack-plane handle or a sad-iron handle, to the base of which is secured, by means of an alcoholic solution of shellac, a piece of felting or other woollen goods B. A hole, D; fig. 3, as indicated by the dotted lines, is bored lengthwise into the lower part of the handle A to be closed by the stopper C. This cavity, represented by dotted lines along the base of fig. 2, is designed to contain scouring-powder. Two forms of the implement are represented in the drawings—fig. 1 with an open handle and without any receptacle for scouring-powder, fig. 2 with a closed handle, as shown by the dotted lines E, and a receptacle for scouring-powder, as shown by the dotted lines running parallel along the base of the handle A.

In cleaning a knife the implement is to be held like a flat-iron, and the felting surface, (either wet or dry,) rubbed on the blade with the interposition of any suitable scouring-powder.

Disclaiming all other forms and combinations of material for knife-cleaners, I claim—

In a knife-cleaner the combination of the handle A having a cavity, D, closed by a stopper, C, and the rubbing surface or layer B arranged, constructed, and operating in the manner as shown and described and for the purpose set forth.

Witnesses:

JNO. A. MARTIN,
JOHN J. INGALLS.
